CLAIM

I claim the ornamental design for a star-shaped pet treat dispensing puzzle, as shown and described.

DESCRIPTION

FIG. 1 is a top perspective view of the uppermost component of a star-shaped pet treat dispensing puzzle, shown separately for clarity, in an unassembled configuration;

FIG. 2 is a top perspective view of the middle component of the star-shaped pet treat dispensing puzzle, shown separately for clarity, in an unassembled configuration;

FIG. 3 is a top perspective view of the base component of the star-shaped pet treat dispensing puzzle, shown separately for clarity, in an unassembled configuration; and,

FIG. 4 is a top perspective view of the star-shaped pet treat dispensing puzzle shown in its assembled condition.

The sides not explicitly shown in the drawings are a mirror image of the sides visible in the drawings.

The appearance of the underside of the star-shaped pet treat dispensing puzzle is not claimed.

This design invention relates to a treat dispensing puzzle toy for pets wherein treats may be inserted into receptacles therefor.
